(57) **CLAIM**

The ornamental design for an electronic commerce terminal enclosure with brackets, as shown and described.

DESCRIPTION

FIG. 1 is a left front perspective view of an electronic commerce terminal enclosure with brackets showing my new design;

FIG. 2 is an enlarged left front perspective view thereof;

FIG. 3 is a right rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an exploded right rear perspective view thereof showing brackets removed for clarity of illustration.

The broken line showing on FIGS. 1-10 is for illustrative purposes only and forms no part of the claimed design.
